ATTORNEYS.

UNITED STATES PATENT OFFICE.

JOSEPH BENCZE, OF YORKVILLE, OHIO.

RAZOR SHARPENER.

Application filed April 27, 1925. Serial No. 26,029.

This invention relates to improvements in 5
razor strops and it is the principal object
of the invention to provide a strop for effec-
tively and positively sharpening razor
blades.

Another object of the invention is the pro-
vision of a strop of simple and inexpensive
construction having a plurality of peculi-
arly shaped openings therein for increasing the
10 stropping effect.

A further object of the invention is the
provision of a razor strop made from canvas
or other fine mesh fabric covered by a rub-
ber composition.

15 These and other objects of my invention
will become more fully known as the descrip-
tion thereof proceeds and will then be more
specifically defined in the appended claim.

In the accompanying drawing, forming a
20 material part of this disclosure:

Fig. 1 is a top plan view of a strop made
according to the invention.

Fig. 2 is a longitudinal section through
the strop, Fig. 1.

25 Fig. 3 is a top plan view of a modified
form of my invention on a somewhat en-
larged scale.

Fig. 4 is a cross-section on line 4—4,
Fig. 3.

30 The strop comprises a strap made of a can-
vas background 10, covered on its top by
means of a smooth face of rubber 11, and
having a handle 12 at one end and an eye
13 at its opposite end allowing the conven-
35 ient suspension of the strop from a nail,
hook, or the like.

The strop illustrated in Figs. 3 and 4 has
a plurality of triangularly shaped openings
14 in its upper face arranged in two sections
40 or groups, one group having the apexes 15 of
the triangles directed in one direction, while
the other group of the openings has the
apexes 16 pointing in the opposite direction.
These openings can be filled with any sub-
45 stance adapted to increase the stropping ac-
tion which, moreover, will be naturally in-
creased or augmented by the somewhat
raised, rubber covered edges of the triangu-
lar holes.

As shown in Fig. 3, the openings in the 50
upper rubber surface of the strop are ar-
ranged in series diagonally across the width
of the strop with the end opening of the
lowermost series adjacent the lower left cor-
ner of the strop and the successive individual 55
openings arranged diagonally thereacross.

It should be understood that the stropping
surface provided in the openings comprises
different material than the upper rubber sur-
face and thus the friction of the blade in 60
passing over these two surfaces is different.
With the diagonal arrangement shown, the
blade may be retained at an angle to the
longitudinal axis of the strop and opposite to
the diagonally arranged openings or it may 65
be held substantially parallel to the width
of the strop and in both cases contact with
both surfaces throughout the entire length
of the strop will exist. The diagonal ar-
rangement thus provided insures a substan- 70
tially constant and uniform frictional re-
sistance to the razor and prevents a jerky
stropping stroke and a shearing action of
the blade relative to the surfacing material
disposed in the holes. 75

It is to be understood that such changes
may be made in the construction of the minor
details of my invention and in its general
arrangement, as fall within the scope of the
 appended claim, without departure from the 80
spirit of my invention.

Having thus described my invention, what
I claim as new and desire to secure by Let-
ters Patent, is:

A razor strap comprising a canvas body, 85
a rubber stropping surface on said body,
diagonally arranged series of units of stropp-
ing composition mounted in said strop,
said series of units being spaced apart to per-
mit uniform engagement of a portion of the 90
blade with said stropping composition and
with said rubber surface during an entire
stropping stroke.

In testimony whereof I have affixed my
signature.

JOSEPH BENCZE.
